UNITED STATES PATENT OFFICE.

ANDREW F. SANBORN, JR., OF PHILADELPHIA, PENNSYLVANIA.

SPRING-SUPPORT FOR HAMMOCKS.

965,839.

Specification of Letters Patent. Patented July 26, 1910.

Application filed June 1, 1910. Serial No. 564,451.

To all whom it may concern:

Be it known that I, ANDREW F. SANBORN, Jr., a citizen of the United States, residing at Philadelphia, in the county of Philadelphia and State of Pennsylvania, have invented certain new and useful Improvements in Spring-Supports for Hammocks, of which the following is a specification.

My invention relates to improvements in 10 spring supports for hammocks, the object of the invention being to provide an attachment for any ordinary hammock which will elastically connect the end of the hammock with its support, and which may be readily 15 connected and disconnected as desired.

A further object is to provide an improved attachment of this character in 20 which the expansion of the springs is limited to prevent injuring the springs, and said springs inclosed in a casing to prevent them from catching the fingers or clothing of persons about the hammock.

With these and other objects in view, the 25 invention consists in certain novel features of construction and combinations and arrangements of parts, as will be more fully hereinafter described and pointed out in the claims.

In the accompanying drawings: Figure 1, 30 is a plan view illustrating my improvements. Fig. 2, is a view in longitudinal section through the center thereof. Fig. 3, is a view in cross section thereof, and Fig. 4, is a perspective view of one of the casing 35 halves.

1, and 2, represent metal loops having bars 3, and 4, respectively located parallel to each other and spaced apart. The loop 1 is adapted to be caught over a hammock support while a snap hook 5 is provided on the loop 2 for connection with the hammock. A 40 plurality of parallel coiled springs 6 are positioned between loops 1, and 2, and have hooked ends 7 caught over the bars 3, and 4, respectively. Any number of these 45 springs may, of course, be employed. In the device illustrated, four are shown, and these springs are inclosed within a metal casing comprising two halves 8, 8, the 50 halves are precisely alike, one of which is shown in perspective in Fig. 4, and they may be cast or of heavy sheet metal.

Each member is provided centrally with a 55 longitudinal depression 9, and these depressions come together and are preferably secured by bolts 10 and nuts 11 to permit the

casing to be removed when desired. At each side of the depression 9, the casing members bulge outward to inclose the two springs at each side of the depression, and 60 the meeting edges of the halves come together as illustrated in Fig. 6. At both ends of both halves, tongues 12 are provided which project over the bars 3, and 4, respectively, and the ends of these halves come 65 together as illustrated at 13 and form, in effect, loops at the ends of the casing confining the bars 3, and 4, and limiting the separation of the bars 3, and 4, from each other, hence limiting the expansion of the 70 springs and preventing their utility being destroyed when an excessive weight is in the hammock. In other words, the expansion of the springs is limited to a certain 75 number of pounds pull and in order to prevent an excessive pull from injuring the attachment, the tongues limit this expansion of the springs. In the event the spring should become ineffective, the casing may be readily removed by removing the bolts 10, 80 and nuts 11, and a new spring placed in position.

Various slight changes might be made in the general form and arrangement of parts 85 described without departing from my invention and hence I do not limit myself to the precise details set forth, but consider myself at liberty to make such changes and alterations as fairly fall within the spirit and scope of the appended claims. 90

Having thus described my invention, what I claim as new and desire to secure by Letters Patent is:

1. A device of the character described, 95 comprising two loops spaced apart, a hook on the outer end of one loop, a series of coiled springs between the loops, hooked ends on the springs caught over bars of the loops, and means limiting the separation of the loops, substantially as described. 100

2. A device of the character described, comprising two loops spaced apart, a hook on the outer end of one loop, a series of coiled springs between the loops, hooked ends on the springs caught over bars of the loops, a casing inclosing the springs, and comprising two halves, and tongues on said halves which when together form elongated loops around bars of the first-mentioned loops limiting the separation of the latter, 110 substantially as described. 105

3. A device of the character described,

comprising two loops spaced apart, a hook on the outer end of one loop, a series of coiled springs between the loops, hooked ends on the springs caught over bars of the 5 loops, a casing inclosing the springs and comprising two halves having longitudinal depressions at their center, bolts and nuts securing said halves together at their longitudinally depressed portions, and loops on 10 the ends of said casing located around bars

of the first-mentioned loops, substantially as described.

In testimony whereof I have signed my name to this specification in the presence of two subscribing witnesses.

ANDREW F. SANBORN, JR.
